UNITED STATES PATENT OFFICE.

FRANCIS WILLIAM KELLY, OF MINNEAPOLIS, MINNESOTA.

WATER-CLOSET FLUSHING-VALVE.

SPECIFICATION forming part of Letters Patent No. 351,835, dated November 2, 1886.

Application filed March 30, 1886. Serial No. 197,145. (No model.)

To all whom it may concern:

Be it known that I, FRANCIS WILLIAM KELLY, a citizen of the United States, and a resident of Minneapolis, in the county of Hennepin and State of Minnesota, have invented 5 certain new and useful Improvements in Water-Closet Flushing-Valves, of which the following specification is a full, clear, and exact description, reference being also had to the accompanying drawings, in which—

Figure 1 is a sectional side view on the line $x x$ of Fig. 2. Fig. 2 is a cross-sectional view on the line $y y$ of Fig. 1; and Fig. 3 is a plan view, with the cover removed, of the flushing-tank and receiving-bowl with my improved valve mechanism arranged in said tank. Fig. 15 4 is an enlarged sectional elevation of the valve-casing and valves.

A' represents the tank for holding the flushing-water; A^2 , the deposit-bowl, the bowl and tank being connected by large pipe A^3 , through which the water from the tank rushes into the bowl.

A^4 is the soil-pipe leading from the bowl A^2 to the sewer-connection A^5 , the latter also connected to the tank A' and with a large valve, A^6 , adapted to close the exit into the sewer. This valve has a stem, a , running up through the cover of the tank and provided with a handle, a' , by which it may be raised. The exit b from the bottom of the tank A' is about the same size as and directly above the valve A^6 , so that when the latter is raised up it will close the bottom exit, b , of the tank and cause 30 all the water in the tank to flow through the connection A^3 into the bowl, and from thence into the sewer-connection through the soil-pipe A^4 .

g' represents the overflow partition and trap, 45 which is placed in one corner of the tank A' , as shown in Figs. 2 and 3, and which is connected, as shown at g^2 in Figs. 2 and 3, with the sewer-connection A^5 .

B' represents a valve-casing united through 50 the bottom of the tank A' by a connection, B^2 , to the water-supply pipe B^3 , the latter taking its water from the hydrant or a large tank above, or from any other suitable source.

B^4 is a side branch leading from the side of 55 the casing B' , and to which the flush-pipe B^5 is connected. This flush-pipe is shown passing out through the side of the tank at d' and

continued into the upper edge of the deposit-bowl A^2 in the ordinary manner.

e' is a valve-seat in the casing B' , just beneath the opening into the side branch, B^4 , and beneath which a valve, e^2 , is adapted to be seated. This valve e^2 is screwed upon a tubular stem, e^3 , which passes upward above the valve e^2 , and is supplied with a piston-head, e^4 , working 60 water-tight against the inner sides of the casing B' .

D' is a rod passing down through the tubular stem e^3 , and provided on its lower end with a small valve, D^2 , adapted to be seated upon the lower end of the tubular stem e^3 , and with a guide, D^3 , in the connection B^2 for its lower end.

The rod D' is smaller than the interior of the tubular stem e^3 , so that water can pass up 70 through the tube around the rod, and to keep the tube in position around the rod when the valve e^2 is open the rod is shown provided with small projections g , which press against the tube and keep the rod centrally therein. The 75 upper end of this rod D' passes out through a stuffing-box, D^4 , in the cover D^5 of the casing B' , and is provided on its upper end, outside the cover D^5 , with a head, D^6 , in which the float-rod E' is pivoted. The shorter end of 80 this float-rod is pivoted at E^2 to the cover D^5 , or to any other fixed part of the valve-casing, while the long end is connected to the float E^3 .

F is a small pipe tapped into the valve-casing B' above the piston e^4 , and bent down into 85 the outer pocket or trap of the overflow g' , so that the water in the overflow will be renewed with fresh water every time the valve is operated.

This tank is more particularly applicable to 90 the form of water-closet shown in my Patent No. 268,025, November 28, 1882, but may be also applied to other forms.

When the large valve A^6 is raised up to discharge the contents of the bowl, the valve is 95 seated by its upper side against the lower side of the opening b in the tank A' , so that all the water above the opening b in the tank must pass into the bowl through the flush-pipe A^3 , and thence escapes by the soil-pipe A^4 . When 100 the main valve A^6 is closed, the water will stand in the tank and bowl at a height sufficient to hold the float E^3 high enough to keep the rod D' elevated, and thus keep the valves e^2 and

D² closed, as shown in Fig. 4. Then, when the main valve A⁶ is opened, the water falling in the tank will cause the float E³ and its rod E' to also fall and push the rod D' downward, and thus open the valve D² and allow the water to rush up through the tubular stem e² into equalizing-chamber B⁶ above the diaphragm or piston-head e⁴, and when a sufficient quantity of water has accumulated therein to overcome the inertia of the piston the latter and the tubular stem e² will be forced downward and open the larger valve, e², and allow the water to pass into the side branch, B⁴, and thence through the flush-pipe B⁵ into the bowl to flush it and replenish it with fresh water. The water will thus continue to flow through the valve e² until the main valve is closed and the water has risen in the tank and bowl to a height sufficient to raise the float E³ high enough to cause its rod E' to raise the rod D, and thus close the valves e² D². In the meantime the water which passed into the equalizing-chamber B⁶ when the valve D² was first opened flows out through the small pipe F and renews the water in the overflow b. The pipe F must be small enough so that the water will flow through it very slowly, so as not to interfere with its proper action on the piston e⁴. By this simple arrangement the replenishing of the tank and bowl is automatically secured by the combined action of the float and double valves e² D².

An important advantage gained by this construction is that a very slight movement of the float and the expenditure of a very small amount of power only is required to operate the valves, it being necessary to open and close the valve D² only, the other valve, e², operating entirely by the action of the water in the equalizing-chamber and being independent of the float.

Having described my invention and set forth its merits, what I claim is—

1. The combination of a valve-casing, B', inserted into the flush-tank A', and having a side

branch, B³, and inlet-pipe B² at its lower end, 45 and with a valve-seat, e¹, below said side branch, a valve, e², adapted to be seated upon said valve-seat, and with a tubular stem, e³, having a piston, e⁴, adapted to fit the interior of said casing above said valve-seat and form an equalizing-chamber, B⁶, in said casing, the pipe F, leading into the said equalizing-chamber, rod D', passing down through said tubular stem, and having valve D², adapted to be seated upon the lower end of said tubular valve-stem, and 55 a float adapted to be raised and lowered by the rising and falling water in said tank to depress and elevate said rod D', and thus open and close said valve D² and permit the water to enter said equalizing-chamber and open said valve e², substantially as described, and for the purpose set forth.

2. The combination, with the tank A', having overflow g', of the valve-casing B', set into said tank and connected to the inlet-pipe B², 65 side branch, B⁴, leading from said valve-casing and connected to discharge-pipe B⁵, valve-seat e' within said casing, valve e², adapted to be seated upon said valve-seat and having tubular stem e³, passing upward through said casing, piston e⁴ on the upper end of said tubular stem and fitting the interior of said casing, rod D', passing downward through said casing and tubular stem, and having valve D² on its lower end, adapted to be seated upon the lower end 70 of said tubular stem, rod E', pivoted to the upper end of said rod D' and having float E³, and pipe F, adapted to replenish said overflow, all operating substantially as described, and for the purpose specified.

In testimony whereof I have hereunto set my hand in presence of two subscribing witnesses.

FRANCIS WILLIAM KELLY.
